UNITED STATES PATENT OFFICE.

FRANTIŠEK VOLECH, OF VRCHLABI, CZECHOSLOVAKIA.

CARD-SAVING DEVICE FOR DOBBY LOOMS.

Application filed October 31, 1924. Serial No. 747,069.

To all whom it may concern:

Be it known that I, FRANTIŠEK VOLECH, residing at Vrchlabi, Czechoslovakia, have invented certain new and useful Improvements in Card-Saving Devices for Dobby Looms, of which the following is a specification.

This invention relates to a card or lag saving device for the change-box motion of 10 dobbi looms and consists, in the combination with a pattern cylinder, of a roller having a helical row of lugs arranged so as to enter successively into engagement with push bars which are selected and positioned by the cylinder and which, when actuated by the lugs, transmit their motion to the change box mechanism. Thus each card or lag will be able to control the weft supply for as many picks as there are lugs 20 on the roller, and a corresponding number of cards will be saved.

Fig. 1 of the accompanying drawings represents a front view of the device, and

Fig. 2, a side view of the same.

In the construction shown in the drawings there are two lifting bars *y* which move the revolver or drop-box in opposite directions, each bar being operated by means of a frame *p*. A plurality of push bars *c* are 30 guided in slots in a plate *d* and abut against the frames *p* for operating the lifting bars. Adjacent push bars belong to different frames. Each push bar has a lug *i* through the medium of which it receives motion from 35 one of a series of lugs *f* connected to a roller *a*. The push bars are normally supported so as to be out of reach of the lugs *f* and are raised into position of co-operation therewith by the pattern cylinder *b* whose 40 lags *e* are for this purpose fitted with pegs *g* in known manner. Thus the push bars will be selected by the pattern cylinder for operation by the roller *a*. The lugs *f* are arranged about the roller *a* in a helical row 45 so as to pass across the lugs of the push bar in regular succession. In the present instance each lug *f* is wide enough to span two push bars, one for each frame *p*, so that either lifting bar *y* will be operated according 50 to the selection made by the pattern cylinder.

There is a ratchet wheel *m* on the shaft of the roller *a*, and a pawl *r* cooperates with this wheel for turning the roller intermittently. There are as many teeth on the 55 ratchet wheel as there are lugs *f* on the roller, so that one lug passes across a pair of push bar lugs each time the roller is operated. A detent pawl *n* which engages a ratchet wheel *z* on the roller shaft, prevents 60 retrograde movement. Both pawls can be disengaged from their wheels by means of a lever *s* when a resetting of the roller is required. The roller shaft has also a tappet *k* which cooperates with a spur wheel *h* 65 connected to the shaft of the cylinder *b* for turning the latter for bringing a fresh card or lag into operation after each complete revolution of the roller *a*.

The card or lag chain *e* may naturally 70 be as long as desired. The number of lifting bars *y* may also be varied, the cards or lags *e*, the lugs *f*, and the grouping of the push bars being modified to correspond.

The mechanism is mounted in a frame *t* 75 and connected by means of the latter to the loom.

I claim:

1. In a card saving device for dobbi looms, the combination with a pattern cylinder 80 and a change-box mechanism, of a plurality of push bars arranged so as to be selected and positioned by said cylinder, a roller having a helical row of lugs arranged so as to operate selected push bars in succession 85 when the roller is rotated, and means for transmitting the motion of said bars to the change-box mechanism.

2. In a card saving device for dobbi looms, the combination with a pattern cylinder 90 and a change-box mechanism, of a plurality of push bars arranged so as to be selected and positioned by said cylinder, a roller having a helical row of lugs arranged so as to operate selected push bars 95 in succession when the roller is rotated, means for rotating said roller intermittently so as to bring the lugs successively into operation, and means for transmitting the movement of the push bars to the change- 100 box mechanism.

3. In a card saving device for dobbi

looms, the combination with a pattern cylinder and a change-box mechanism, of a plurality of push bars arranged so as to be selected and positioned by said cylinder, a 5 roller having a helical row of lugs arranged so as to operate selected push bars in succession when the roller is rotated, means for rotating said roller intermittently so as to bring the lugs successively into operation, a

spur wheel connected to the cylinder shaft, a 10 tappet arranged on the roller shaft so as to cooperate with said spur wheel and move the cylinder once for each revolution of the roller, and means for transmitting the movement of the push bars to the change-box 15 mechanism.

FRANTIŠEK VOLECH.
